ULTRA HIGH FREQUENCY ELECTRIC
DISCHARGE DEVICEJames M. Lafferty, Colonie, N. Y., assignor to
General Electric Company, a corporation of
New York

Application October 16, 1943, Serial No. 506,501

12 Claims. (Cl. 315—5)

1

My invention relates to ultra high frequency electric discharge devices and, more particularly, to ultra high frequency electric discharge devices of the space resonant type employing velocity modulation principles.

In my copending application, Serial No. 477,065, filed February 25, 1943, now Patent No. 2,421,273, granted May 27, 1947, and entitled "Ultra high frequency electric discharge system," and assigned to the same assignee as the present invention, I disclose an ultra high frequency oscillator of the reflex velocity modulation type in which a space resonant cavity is provided. The operating frequency of the device is controlled either by mechanical means, which adjusts the position of a tuning diaphragm, or electrically by controlling the potentials of retarding and repelling electrodes with respect to an anode structure. My present invention is directed to certain improvements in an ultra high frequency electric discharge device of this type.

It is an object of my invention to provide a new and improved ultra high frequency electric discharge device or oscillator of the velocity modulation type.

It is another object of my invention to provide a new and improved composite electrode structure for an ultra high frequency electric discharge device.

It is a further object of my invention to provide new and improved means for cooling the anode of a reflex type velocity modulation discharge device.

It is a still further object of my invention to provide a new and improved method of forming a cavity resonator.

It is still another object of my invention to provide a new and improved anode structure for an ultra high frequency electric discharge device of the space resonant type.

In accordance with one aspect of my invention, I provide a new and improved electric discharge device employing velocity modulation principles and including a metallic enclosing envelope wherein a cylindrical heat conducting member disposed within the envelope is in thermal contact with, and mechanically supports a disk-type anode structure having a centrally located apertured space resonant cavity, the anode structure serving to support a plurality of associated electrodes by means of insulating cylinders hermetically sealed between arms extending from the anode structure and the electrodes.

A further feature of my invention relates to an improved anode structure of the cavity resonator

2

type and having a deformable diaphragm constituting one boundary of said cavity, the diaphragm and a surface of the anode disk forming a half wave choke included in the cavity resonator.

A still further feature of my invention relates to the construction of a reentrant type cavity resonator wherein a soft malleable metal member, formed to the exact shape of the cavity, is electropated with a good electrically conductive metal to form cavity walls of desired thickness, the soft metal being thereafter removed by means of a suitable acid.

For a better understanding of my invention, reference may be had to the following description taken in connection with the accompanying drawings and its scope will be pointed out in the appended claims. Fig. 1 is a longitudinal view, partly in cross section, of an electric discharge device of the velocity modulation type built in accordance with my invention. Figs. 2-5, inclusive, are detailed cross sectional views of this discharge device. Fig. 6 is a modification of the anode structure used in the device shown in Fig. 1 and illustrates steps in the method employed for forming a cavity resonator. Fig. 7 is a cross sectional view of an anode structure employing the cavity resonator of Fig. 6. Fig. 8 is an enlarged diagrammatic sketch showing a possible distribution of equipotential lines of force in the retarding and reversing regions of the discharge device, and which also illustrates the paths of electrons having different amounts of energy and the probable paths of such electrons. Fig. 9 shows the manner of variation of the radio frequency or the ultra high frequency modulating voltage which appears across the modulating gap within the space resonant cavity.

Referring now to Fig. 1, my invention is there illustrated as applied to an ultra high frequency electric discharge device comprising an enclosing envelope 1, preferably of rigid construction, comprising a metal having a low coefficient of thermal expansion such as Invar, and which defines at least in part an evacuated space within which are positioned the various elements or electrodes described hereinafter. The envelope 1 is supported by and sealed to a base member 2 which comprises a flanged metallic part 3 upon which the lower end of envelope 1 is seated and to which it is secured by a suitable sealing means, such as a solder 4. A flanged member 5, having a portion opposed to flange 3, is attached thereto in any suitable manner, as by welding. A plurality of prongs or terminal posts 6-10, inclusive, are

supported by an insulating part 12 of base member 2 in insulated relation and serve as externally accessible contacts for the electrodes of the discharge device. Of the aforementioned five terminal posts, four are visible in Fig. 1, terminal post 10 being shown in Fig. 2.

An orientation protuberance for guiding the insertion of base member 2 and the terminal posts into an associated socket is provided and is preferably centrally located. The orientation protuberance may comprise a tubular extension 13 of insulating material formed integral with part 12 and having a central opening through which extends a concentric transmission line comprising an inner conductor 14 and an outer tubular conductor 15 which is sealingly attached to the top surface of part 2 by means of a metallic sleeve or eyelet 17 of any suitable material, such as fernico. The transmission line just described is supported near its upper end by means of a sealing insulator 18 within sleeve 17 and which not only serves as mechanical support and positioning means for the inner conductor 14, but also serves as the means for sealing these elements to maintain a desired degree of evacuation within the envelope of the discharge device.

Within the envelope 1 and preferably centrally located near the lower part of the defined space, I provide a thermionic cathode which may be of the indirectly heated type comprising a metallic cylinder 19, preferably coated on the exterior of the upper closed end with an electron emissive material, such as an alkaline earth metal, to serve as a source of electrons. A filament or heating element 20 is centrally positioned within the cylinder 19 and is supplied with energizing current through a pair of conductors 21, 22, conductor 21 being connected between one end of filament 20 and terminal post 7 and conductor 22 (shown in Fig. 2) being connected to the terminal post 10. The other end 23 of filament 20 is welded directly to the outer surface of metallic cylinder 19 at its lower extremity. An electrostatic shield comprising a flanged cylinder 24 is welded to the exterior surface of cathode cylinder 19 and supported from a metallic disk 25 by means of a plurality of small wires 26, welded between parts 24 and 25. Conductor 22 may be welded directly to disk 25.

An anode structure defining a space resonant cavity or region is provided comprising a substantially disk-shaped metallic part 27 and is preferably constructed of an iron block which is lightly sand-blasted and then plated with a suitable conductive material, such as copper. Thereafter the block is heated in an atmosphere of hydrogen to melt the copper to increase its conductivity, the sand-blasting operation serving to prevent puddling of the copper to assure a uniform distribution of the copper after the heating. The anode block 27 is supported by and thermally connected to a cylindrical heat conducting member 28, formed of a suitable metal having a low coefficient of thermal expansion, such as Invar, the block 27 being attached thereto by spot welding. The heat conducting member 28 may be corrugated, as shown, and have an outer diameter such that it slips within the envelope 1 making thermal contact therewith at each corrugation. At its lower end member 28 fits around the upper end of base 2, being attached thereto as by welding.

At the central part of the block 27, there is provided a central opening defining a space resonant region or cavity 29. The details of the

anode structure are shown in Figs. 4 and 5, the former of which is a plan view and the latter of which is an enlarged cross sectional view. The block 27 is provided with a plurality of recesses 30 into which extend an equal number of radially extending metallic arms 31 attached at their inner ends to the block 27. An additional recess 32 is provided which is in communication with the space resonant cavity 29 through a radial opening 34, preferably of circular cross section, and which houses one end of a concentric transmission line 35, shown in Figs. 1 and 2.

As a means for defining one boundary of the space resonant cavity 29 and also for providing an entrance and directing structure for the electron beam, member 37 is provided preferably constructed of metal, such as copper, and which is adapted to be seated in a recess in the bottom face of block 27. The member 37 includes a conical part 38 having a tapered aperture 39 through which the electron beam passes and which defines with one boundary of the space resonant cavity 29 a velocity modulating gap 40 for the electrons constituting the beam.

In order to control the natural frequency by controlling the physical dimensions of the space resonant cavity 29, a deformable member, such as a flexible metallic diaphragm 41, is provided, which at its outer edge, is seated upon a circular flange 42 extending upwardly from the top surface of block 27 to constitute one boundary of the cavity 29. The diaphragm 41 is provided with a central aperture 43 to afford a communicating path between the cavity and the electron retarding and reversing regions described hereinafter. The radial distance from the central opening in anode block 27 to the inner surface of the circular flange 42 is made approximately equal to a half wave length at the desired operating frequency of the electric discharge device so that the diaphragm 41 and the top surface of block 27 between the resonant cavity 29 and flange 42 form a section of radial transmission line of a length such that the short-circuit at one end, constituted by the flange 42, is reproduced to appear as a very low impedance at the inner end of this section of radial transmission line. The disk 41 and the upper surface of block 27 are provided with a plurality of corresponding and concentric grooves 44, the function of which is pointed out in detail hereinafter.

Returning now to Fig. 1, control electrode means are provided for establishing electron repelling and retarding electric fields and which may take the form of a pair of disks 46 and 47, the latter disk being provided with central aperture 49 to permit the passage of electrons therethrough into the region defined between disks 46 and 47 or to produce the proper electric fields in the vicinity of aperture 49. Each of the disks 46 and 47 is provided with a plurality of radially extending metallic arms 48 overlying and corresponding to the arms 31 attached to anode block 27. Disk 25, supporting the thermionic cathode structure, likewise is provided with radially extending arms 48. In order to insulate the respective electrodes from the anode block 27, as well as to support these electrodes from anode block 27 and indirectly from heat conducting member 28, a plurality of insulators 50 of a suitable material, such as glass, are hermetically sealed to the arms 31 and 48.

In order to impress suitable potentials on the disks 46 and 47, a pair of conductors 52 and

53, as shown in Fig. 3, are provided, which extend respectively through apertures 54 and 55 of anode disk 27 and are connected to cross conductors 52, 53' conductively joined respectively to the above-mentioned disks. Conductor 52' may be connected to a central terminal post 56 attached to disk 46, while conductor 53' may be connected to the terminal 57 attached to the edge of the disk 47. Also connected between conductors 52 and 53 and a conductor 58, soldered or welded at its lower end to an aperture 59 in the anode block 27, are a pair of fusible conductors 60 which may comprise gettering means for the discharge device after it has been evacuated.

To focus the electrons emitted at the upper end of cathode cylinder 19 a focusing electrode means are employed, which may comprise a cylinder 61 supplied with a plurality of radially extending arms 62 embedded in the insulating cylinders 50. A suitable negative focusing potential may be impressed on cylinder 61 by means of a conductor 63 which is attached to an additional arm 64 extending radially outwardly from cylinder 61 and which is connected to terminal post 6 through a lead-in wire 65.

In order to derive ultra high frequency energy from cavity 29, a curved ultra high frequency concentric transmission line 35 extends from that cavity to the base member 2 to facilitate external connection to the device. The concentric transmission line comprises an inner conductor 67 and an outer tubular conductor 68 separated by a pulverized insulator, such as a vitreous material 69 which may be quartz. The inner conductor 67 extends into the cavity 29 and serves as an output electrode means and may take the form of a loop 70, whereby the transmission line is coupled to the cavity. The lower extremity of the transmission line comprising conductors 67 and 68 is provided with an adaptor assembly 71 which comprises a recessed metallic cylinder 71 supported at the lower end of the outer conductor 68. Within the recess of cylinder 71 there is provided an adaptor for the inner conductor 67 which comprises a metallic part 72, in turn being provided with a recess at its lower end which engages the upper end of inner conductor 14 of the transmission line supported within the tubular extension 13 of the discharge device. The outside diameter of cylinder 71 is chosen so that the adaptor assembly snugly fits the inner surface of eyelet 17.

To assure good electrical contact between cylinder 71 and eyelet 17 and between conductor 14 and part 72, respectively, the outer surfaces of cylinder 71 and the inner surface of part 72 are tinned prior to the assembly operation. After assembly of the elements in the positions shown in Fig. 1, after the application of heat thereto, the tin forms a firm connection between the elements, that is, between cylinder 71 and the inner surface of eyelet 17 and between conductor 14 and part 72, respectively.

As a means for mechanically controlling the form and position of the diaphragm 41, an externally accessible actuating means is employed for exerting different amounts of pressure thereon, thereby controlling the dimensions of the space resonant cavity 29. This means may comprise an assembly supported by the flat top of the envelope 1 and may include an actuating rod 75 constituting a vertically adjustable or positionable member of the actuating means. Rod 75 is connected to the diaphragm 41 by a pair of vertical wires 76 and 77 and a cross piece 78, the

latter being welded to rod 75 and wires 76 and 77 being welded to cross piece 78. At their lower ends, the wires 76 and 77 are seated in one of the grooves 44 in the upper surface of diaphragm 41 and may be permanently attached thereto, as by soldering. Alternatively, instead of the wires 76, 77 being soldered or welded to the diaphragm 41, these rods or wires may be seated in an annular groove provided in the diaphragm and the diaphragm formed to have a resiliency tending to restore itself to an upward or vertical position whereupon the diaphragm is maintained in contact with rods 76 and 77. In such instance, the control of the form of the diaphragm is accomplished by the amount of downward vertical pressure exerted thereagainst. Surrounding the vertical rod 75 is a hollow tuning screw 80 which is welded or brazed around the top of rod 75 to form a vacuum-tight seal. At its lower end, the hollow tuning screw 80 is welded or soldered to a metallic bellows 81 sealed to the inner surface of envelope 1 to provide a sealing structure of deformable character for the upper portion of the envelope.

Above the envelope 1 and in an externally accessible position, a micrometer adjustment means 82 is provided to actuate rod 75 whereby, upon actuation, the rod 75 is moved to position the diaphragm 41 in minutely determinable degrees to obtain a desired control in the operating frequency of the device. Preferably, the rod 75, cross piece 78, wires 76, 77, tuning screw 80, and micrometer 82, are composed, similar to envelope 1 and member 28, of a metal having a low coefficient of thermal expansion, Invar being well suited for this construction. So constructed, the device experiences little change in operating frequency as the operating temperature varies.

Fig. 2 is a cross sectional view of the discharge device shown in Fig. 1 along the lines 2-2 and represents the arrangement of some of the conductors, particularly the connections 21 and 22 to the cathode. Also shown in this view and in the vertical view in Fig. 1 is an exhaust tubulation 84 for producing a desired vacuum within the electric discharge device. Fig. 3 is a cross sectional view of the discharge device shown in Fig. 1 along the line 3-3 and represents the arrangement of other conductors, particularly the connections to the gettering means 60. After the discharge device has been exhausted through tubulation 84 and later sealed at its lower tip in the usual manner, conductors 52 and 53 are connected together externally and voltage impressed between conductor 58 and conductors 52, 53 to flash the vaporizing material supported about fusible conductors 60 in order to absorb occluded gases.

Referring now to Fig. 6, I have there shown a modification of the cavity resonator employed in the anode of my electric discharge device and have illustrated certain steps in the process of forming this cavity resonator. In constructing the cavity resonator 86, I form a pellet 87 of a soft malleable metal, such as zinc, to the exact shape of the cavity, stamping the pellet to this shape by means of a punch and die. The stamped pellet is then electroplated with a suitable metal having high electrical conductivity, such as copper or any other metal in the first group of the periodic table of elements. In the step of electroplating the zinc pellet 87, an electrode 88 is attached to one of the walls of the pellet, in the case of the particular pellet shown, to a side wall. After the pellet has been electroplated until a deposit of a desired

thickness is obtained so that walls of the cavity resonator 86 have a sufficient strength, the electrode 88 is removed and small concentric holes, corresponding to the hole 43 shown in Fig. 5, are drilled through the conical section 38' and the upper wall 41' of the cavity resonator 86. Thereafter, the composite structure is placed in a bath of suitable acid, such as concentrated hydrochloric acid, to remove the soft metal pellet 87, leaving a thin shell of the hard metal having the exact form of the resonant cavity. To this end, the metal of the pellet 87 should lie above hydrogen in the electromotive series, while the metal forming the walls of resonator 86 should lie below hydrogen in the electromotive series. By this process, the intricate machining operations required in the cavity structure shown in Figs. 1 and 5 are avoided, while exact alignment of the holes through wall 41' and the cone 38' is obtained. Moreover, any desired intricacy of the reentrant cone design may be obtained with ease and facility.

In Fig. 7, I have shown a modification of the anode block 27' used in conjunction with the cavity resonator 86 formed in accordance with the process described above. In Figs. 6 and 7, elements corresponding to elements illustrated and described in Figs. 1 and 5 are designated by the primes of corresponding reference numerals. The block 27' is provided with a central opening having a shoulder portion 89 upon which the cavity resonator 86 is placed. The opening formed in the side wall of resonator 86 when electrode 88 is removed provides a means for introducing the coupling loop 79' at the end of the concentric transmission line comprising inner conductor 67' and outer tubular conductor 68'.

The operation of the embodiments of my invention described above will be considered with particular reference to Fig. 1 and the schematic arrangement of certain of the electrode elements shown in Fig. 8, when the device is operating as an oscillator. Generally speaking, the electric discharge device is of the velocity modulation type wherein the electron beam is velocity modulated periodically so that successive groups of electrons are alternately accelerated and decelerated, tending to group the electrons in the beam after the beam has traversed the velocity modulation gap. The particular form of electric discharge device described above operates in accordance with reflex principles. After undergoing velocity modulations, the electrons are given an opportunity to assume a charge density distribution incident to the effect of the velocity modulation and are reversed in the direction of travel to reenter the space resonant cavity, delivering energy to the electromagnetic field thereof or to an associated electrode construction. In the device described above, an electron beam is established by virtue of a unidirectional potential impressed across the anode structure comprising block 27 and cathode cylinder 13. The electrons of the electron beam initially assume a velocity determined by the accelerating potential impressed on the anode structure. A negative potential with respect to the cathode cylinder 13 is impressed on the focusing cylinder 61 which tends to restrict the size of the electron beam, confining it to a relatively small transverse area in order that a large percentage of the electrons pass through the space resonant cavity 29 through the conical part 38. Assuming an excitation of the cavity 29 by virtue of sporadic motion of the electrons therethrough during the starting operation, cavity 29 is set into oscilla-

tion and there is established across the modulating gap 40 an alternating ultra high frequency potential incident to the electromagnetic field within the cavity 29. By virtue of the alternating nature of this potential, electrons which are in the effective region of gap 40 during periods of time when the diaphragm 41 is positive with respect to the conical part 38 will undergo an acceleration. The curve A in Fig. 9 represents the radio frequency voltage appearing across the modulating gap 40. Consequently, the electrons after traversing the space resonant cavity 29 proceed through aperture 43 of diaphragm 41 into the region of the field produced by the focusing and retarding electrode 47, which may be maintained at a negative potential with respect to the anode. Furthermore, the potential of the retarding electrode 47 may also be negative with respect to the cathode, as well as being negative to the anode structure. The distance which the electrons proceed in their paths beyond diaphragm 41 is a function of the kinetic energy of each electron. It is well understood that the energy of an electron may be referred to a voltage which will accelerate the electron to a particular velocity establishing the kinetic energy of the electrons, and consequently the kinetic energy of the electrons may be referred to a retarding field which is just sufficient to stop the motion of the electrons. The faster electrons obviously travel farther in this field before they are stopped or reversed than the slower electrons.

The probable paths of electrons within the fields produced by retarding electrode 47 and repelling electrode 46 are represented by curves a, b, and c in Fig. 8. The field distribution is plotted showing only one half the region and it is understood that the other half region is similar to that illustrated. The curved lines extending from diaphragm 41 to the conical part 38 represent the contour of the electric lines of force present in the cavity during one half cycle, that is, the positive half cycle, during which the electrons are accelerated. The circled crosses represent the corresponding direction of the magnetic component of electromagnetic field during the same half cycle. During a half cycle of opposite polarity, the electric component and the magnetic component, of course, are reversed in direction. The curve a represents the path of a low velocity electron which traverses a distance and is reversed in its direction of travel and focused so that it reenters the cavity 29. An electron of greater kinetic energy corresponding in its path to curve b travels a greater distance before reversal and, as illustrated, is reversed within the vicinity of a zero potential line. Lastly, an electron of even greater velocity proceeds in the direction of the repelling electrode 46 and enters the negative field produced thereby, undergoing a reversal in the region of the negative potential electric field.

The operating frequency of an electric discharge device may be controlled either by controlling the physical dimensions of the space resonant cavity 29 or by controlling the voltage impressed upon the electrodes, including the voltage on the anode structure and the voltage on the electrodes 46 and 47. Considering first the control of the operating frequency by virtue of the change in the physical dimensions of the cavity, the position of the diaphragm 41 controls one boundary of the cavity and consequently controls its natural frequency. Ready adjustment of the position of diaphragm 41 is obtained by manipulation of the micrometer 82. It has

been found that in electric discharge devices built in accordance with the above described principles and construction, the operating frequency of the discharge device may be varied throughout a range of 6000 megacycles and that the discharge device has an effective and substantial power output when producing a wave having a wave length of the order of one centimeter.

The operating frequency, as stated above, may also be controlled by variation of the voltages impressed on the repelling electrode 46 and the retarding electrode 47, in this manner controlling the transit time of the electrons in the beam and consequently controlling the phase of the charge-density modulated electrons which are returned to the space resonant cavity 29 with respect to the field thereof. By using this method of controlling the operating frequency, it has been found that an additional finer adjustment of range of 90 megacycles frequency control may be obtained. The above described construction of an ultra high frequency electric discharge device, moreover, is peculiarly adaptable for the production of discharge devices of exceedingly small size.

While I have shown particular embodiments of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. An ultra high frequency electric discharge device of the velocity modulation type comprising an enclosing metallic envelope, a cylindrical heat conducting member disposed within said envelope and in thermal contact therewith at a plurality of points, a disk-type anode structure supported by and in thermal contact with said cylindrical member, said anode structure including a centrally located, apertured cavity resonator, a thermionic cathode positioned below said anode structure, a disk-type repelling electrode positioned above said anode structure, and a plurality of insulating members hermetically sealed to all said electrodes supporting said cathode and said repelling electrode from said anode structure in spaced relation therewith.

2. An ultra high frequency electric discharge device of the velocity modulation type comprising an enclosing envelope, a base member supporting said envelope, a cylindrical heat conducting member in thermal contact with the inner surface of said envelope and supported by said base member, a disk-type anode supported by and in thermal contact with said cylindrical member, said anode including a centrally located, apertured cavity resonator, a thermionic cathode positioned below said anode structure, an apertured retarding electrode positioned above said anode structure, a repelling electrode positioned above said retarding electrode, each of said anode, cathode, and electrodes having a metallic arm extending outwardly from the active surface thereof, a cylindrical insulator hermetically sealed to said arms supporting said cathode and electrodes from said anode and maintaining said anode, cathode, and electrodes in spaced relation, means within said base member whereby operating potentials may be impressed upon said electrodes, means connected to said resonator for tuning said cavity resonator and externally accessible actuating means for said tuning means supported by said envelope.

3. An ultra high frequency electric discharge device of the velocity modulation type comprising an enclosing metallic envelope, a base member supporting said envelope, a cylindrical heat conducting member in thermal contact with the inner surface of said envelope and supported by said base member, a disk-type anode supported by and in thermal contact with said cylindrical member, a plurality of electrodes supported by and in insulated spaced relation with said anode said electrodes including a cathode for producing an electron beam with said anode, said anode including a cavity resonator and being provided with an inwardly extending part through which the electrons may pass to enter said cavity resonator and which defines therewith a velocity modulation gap, electrode means beyond said anode for reversing the electrons after traversing said cavity resonator to cause said electrons to enter said cavity resonator and deliver energy to the electromagnetic field thereof, means within said base member whereby operating potentials may be impressed upon said electrodes, means connected to said resonator for tuning said cavity resonator, and externally accessible actuating means for said tuning means supported by said envelope.

4. A composite electrode structure for an ultra high frequency electric discharge device of the velocity modulation type comprising, a horizontal disk-type anode structure defining an apertured cavity resonator, a thermionic cathode positioned below said anode structure, an apertured retarding electrode positioned above said anode structure, a repelling electrode positioned above said retarding electrode, each of said anode structure, cathode, and electrodes having a metallic arm extending outwardly from the active surface thereof, an insulating member hermetically sealed to said arms supporting said cathode and electrodes from said anode structure and maintaining said anode structure, cathode, and electrodes in spaced relation, and a vertical cylindrical heat conducting member thermally and mechanically connected to said anode structure at its outer periphery.

5. An anode structure for an ultra high frequency electric discharge device of the cavity resonator type comprising a metallic disk having a circular, centrally positioned opening therethrough defining in part a cavity resonator, an inwardly extending apertured conical member extending across the bottom of said opening defining one boundary of said cavity resonator, a circular flange extending upwardly from the top surface of said disk at a radial distance from the circumference of said opening equal to a half wave length at the operating frequency of said device, and a deformable diaphragm hermetically sealed across said flange constituting an opposite boundary of said cavity resonator and forming with said top surface a section of radial transmission line.

6. An anode structure for an ultra high frequency electric discharge device of the cavity resonator type comprising a metallic disk having a circular, centrally positioned opening therethrough defining in part a cavity resonator, an inwardly extending, apertured conical member extending across the bottom of said opening defining one boundary of said cavity resonator, a circular flange extending upwardly from the top surface of said disk at a radial distance from the circumference of said opening equal to a half wave length at the operating frequency of said

11

device, a deformable diaphragm hermetically sealed across said flange constituting an opposite boundary of said cavity resonator and forming with said top surface a section of radial transmission line, and pressure activated means connected to said diaphragm for effecting controllable deformation thereof whereby the natural frequency of said cavity resonator may be controlled.

7. An anode structure for an ultra high frequency discharge device of the cavity resonator type comprising a metallic disk having a centrally positioned opening defining in part a cavity resonator, an entrance part for receiving electrons and producing a narrowly defined control region within said cavity resonator comprising an apertured metal cone constituting one boundary of said cavity resonator, a circular flange extending upwardly from the top surface of said disk at a radial distance from said opening equal to a half wave length at the operating frequency of said device, a deformable diaphragm connected across said flange constituting an opposite boundary of said cavity resonator and forming with said top surface a section of radial transmission line, and a transverse metal rod connected to the outer surface of said diaphragm at a point between said opening and said flange whereby different amounts of pressure may be exerted on said diaphragm to control the natural frequency of said cavity resonator.

8. An ultra high frequency electric discharge device of the velocity modulation type comprising an enclosing envelope, a heat conducting member disposed within said envelope and in thermal contact therewith at a plurality of points, an electrode structure in thermal contact with said heat conducting member, said electrode structure including a cavity resonator, and externally accessible means for tuning said cavity resonator supported by said envelope, said envelope, said heat conducting member and said tuning means being formed of a metal having a low coefficient of thermal expansion to minimize variation in the operating frequency of said device with variation in the operating temperature thereof.

9. An electron discharge device comprising an enclosing envelope having a base portion and a cylindrical metallic wall portion, a cylindrical heat conductive member within said envelope supported on said base member and having thermal contact with said wall portion at a plurality of points, a pair of electrodes disposed within said envelope, one of said electrodes comprising an anode supported from said member by thermally conductive means, and insulating means supporting the other of said electrodes from said anode.

10. A cavity resonator comprising a hollow metallic member having a pair of parallel walls and a side wall integrally united with said parallel walls, one of said parallel walls having a centrally positioned opening therein, the other of

12

said parallel walls having an inwardly extending cone-shaped part, said part terminating in a second opening aligned with the first of said openings, said one wall having a circular ridge therein concentric with said openings to permit flexing of said one wall to vary the distance between said parallel walls.

11. A cavity resonator comprising a hollow metallic member having a pair of parallel walls and a side wall integrally united with said parallel walls, one of said parallel walls having a centrally positioned opening therein, the other of said parallel walls having an inwardly extending cone-shaped part, said part terminating in a second opening aligned with the first of said openings, said one wall having a circular ridge therein concentric with said openings to permit flexing of said one wall to vary the distance between said parallel walls, said side wall having an opening therein, and output electrode means extending into said resonator through said opening in said side wall.

12. An ultra high frequency electric discharge device of the velocity modulation type comprising an enclosed metallic envelope, a heat conducting member disposed within said envelope in thermal contact therewith at a plurality of points and substantially surrounding a plurality of electrodes, said electrodes comprising an anode supported by and in thermal contact with said member and including a centrally located, apertured cavity resonator, a thermionic cathode positioned below said anode, a repelling electrode positioned above said anode, and a plurality of insulating members sealed to all of said electrodes supporting said cathode and said repelling electrode from said anode in spaced relation therewith.

JAMES M. LAFFERTY.

Certificate of Correction

Patent No. 2,454,970.

November 30, 1948.

JAMES M. LAFFERTY

It is hereby certified that errors appear in the printed specification of the above numbered patent requiring correction as follows:

Column 9, line 73, claim 2, after the word "resonator" insert a comma; column 12, line 25, claim 12, for "enclosed" read *enclosing*; and that the said Letters Patent should be read with these corrections therein that the same may conform to the record of the case in the Patent Office.

Signed and sealed this 21st day of June, A. D. 1949:

[SEAL]

THOMAS F. MURPHY,
Assistant Commissioner of Patents.
